UNITED STATES PATENT OFFICE.

GEORGE F. WAKEFIELD, OF SAN JOSE, CALIFORNIA.

COMBINED BANK-CHECK AND RECORD BOOK.

1,200,056.

Specification of Letters Patent.

Patented Oct. 3, 1916.

Application filed January 12, 1916. Serial No. 71,718.

To all whom it may concern:

Be it known that I, GEORGE F. WAKEFIELD, a citizen of the United States, residing at San Jose, in the county of Santa Clara and State of California, have invented new and useful Improvements in Combined Bank-Check and Record Books, of which the following is a specification.

My invention relates to a folding cover 10 for containing a quantity of blank checks, upon one leaf of the cover and in convenient relation thereto, upon the opposite cover, a ruled record book in which may be entered deposits, checks withdrawn and balance 15 remaining, so that the state of the account is presented at a glance at all times upon opening the book.

It consists in the construction and arrangement of the different elements and in 20 details which will be more fully explained by reference to the accompanying drawings in which—

Figure 1 is a plan view of the book when open. Fig. 2 is a similar view with the 25 record sheets rolled up and part of the check broken out, and a portion of the blotting pad in place over the check pad. Fig. 3 is an end elevation of the record book in folded or closed position; and, Fig. 4 is an 30 inverted section on the line 4—4 of Fig. 1.

It is the object of my invention to improve the efficiency of check books, particularly designed for pocket use, by placing adjacent to the check pad a record on which 35 may be entered the amounts drawn, deposits made and balance remaining, and attaching said checks and record to an inclosing cover. The cover A is made of cardboard, leather, or other material, and is foldable along the 40 center. The checks 2 are united so that they may be conveniently separated along the left edge as they are used. The checks are designed to lie upon the lower half of the cover and parallel with the central fold or 45 hinge 3.

In order to secure the checks to the cover a strip or loop 4 has its ends fixed so that the strip extends across the left end of this half of the cover. A tongue 5 is fixed to 50 the left end of the pad of checks and may be inserted beneath the keeper strip 4, thus holding the checks securely while allowing them to be moved or replaced bodily. The other and upper half of the cover has four

keeper strips 6 fixed at the corners and 55 these are adapted to receive the corners of a supplemental cover 7 which has, foldable centrally and transversely of the outer main cover, a blank book, with vertical lines forming spaces for dates, entries, deposits, checks 60 drawn, and final balances, so that each transaction and the actual balance on hand is shown. The cover 7 and the leaves borne thereby fold on the line 10, which line divides the leaves into two sections 11 and 12 65 both being rolled up in Fig. 2 to show the cover 7. As shown in Fig. 2, a blotting pad P may be employed and placed over the checks 2; the pad being omitted from Fig. 1. When the record book is closed, as shown 70 in Fig. 3, it may be conveniently filed away as a permanent record. With this device, when the book is opened, the personal record and cash balance are exposed to view at a single operation. A check may be written 75 or a deposit entered, and with a blotter lying between, the closing of the book will blot the entries, after which, by again opening it, the check may be detached. The record book will serve for a long time, while 80 the checks may be easily replaced when exhausted. By making the outer cover wider, two sets of checks and two record books may be contained and separate accounts may be carried in the one device. 85

Having thus described my invention, what I claim and desire to secure by Letters Patent is—

In a combined bank check and record book, a main foldable cover, a pad of blank 90 checks carried by the main cover on one side of the line of fold thereof, a blank book having a foldable cover which is carried by the other side of the main cover with the leaves of the blank book open, said blank 95 book having a central line of fold at right angles to the line of fold of the main cover, and means on the last named side of the main cover to hold the blank book cover open. 100

In testimony whereof I have hereunto set my hand in the presence of two subscribing witnesses.

GEORGE F. WAKEFIELD.
